CONTROL UNIT FOR A TWO-WAY RADIO OR SIMILAR ARTICLE

Martin C. Stessel, Schaumberg, Rudolph W. Kroopp,
Palatine, and Karl Miklas, Park Ridge, Ill., assignors to
Motorola, Inc., Franklin Park, Ill.

Filed Feb. 24, 1970, Ser. No. 21,630

Term of patent 14 years

Int. Cl. D14—03

U.S. Cl. D26—14

FIG. 1

FIG. 2

FIG. 3

FIG. 4

FIG. 5

FIG. 6

FIG. 1 is a front prospective view of a control unit for a two-way radio or similar article, showing our new design;

FIG. 2 is a rear prospective view of the control unit shown in FIG. 1;

FIG. 3 is a side view of the control unit;

FIG. 4 is a front view of the control unit;

FIG. 5 is a rear view of the control unit; and

FIG. 6 is a bottom plan view of the control unit.

We claim:

The ornamental design for a control unit for a two-way radio or similar article, as shown and described.
